DESIGN FOR AN ARMCHAIR

Frederick T. Paden, Collingswood, N. J.

Application January 13, 1948, Serial No. 143,699

Term of patent 3½ years

(Cl. D15—1)

To all whom it may concern:

Be it known that I, Frederick T. Paden, a citizen of the United States of America, residing at Collingswood, in the county of Camden and State of New Jersey, have invented a new, original, and ornamental Design for an Arm Chair, of which the following is a specification, reference being had to the accompanying drawings, forming a part thereof.

Figure 1 is a perspective view of an arm chair, showing my new design;

Figure 2 is a front view of the same;

Figure 3 is a side view of the same; and

Figure 4 is a rear view of the same.

I claim:

The ornamental design for an arm chair, as shown.

FREDERICK T. PADEN.
